(57) **CLAIM**

The ornamental design for an animal deterrent device, as shown and described.

DESCRIPTION

FIG. 1 is a first elevated perspective view of an animal deterrent device, according to our new design;

FIG. 2 is a second elevated perspective view of the animal deterrent device;

FIG. 3 is a front view of the animal deterrent device;

FIG. 4 is a rear view of the animal deterrent device;

FIG. 5 is a first side view of the animal deterrent device;

FIG. 6 is a second side of the animal deterrent device;

FIG. 7 is a top view of the animal deterrent device; and,

FIG. 8 is a bottom view of the animal deterrent device.

The portions shown in broken lines comprise environmental structure only and form no part of the claimed design.
